UNITED STATES PATENT OFFICE

2,613,973

REFRIGERATOR DOOR LOCKING AND
OPENING MECHANISMPaul H. Brinkoeter, San Antonio, Tex., assignor
to Ed. Friedrich, Inc., San Antonio, Tex., a cor-
poration of Texas

Application May 23, 1949, Serial No. 94,848

1 Claim. (Cl. 292—255)

1

My invention relates to concealed locks and lock releasing means operated by a foot pedal to unlatch the door and enable the door to be thrown open to approximately a 45° angle.

I am aware that refrigerator door latches with foot pedal or treadle release means have heretofore been provided but all those that have come to my attention are defective in one way or another. Either they are too expensive to construct and maintain, or they have some mechanical defect which renders them unreliable.

It is therefore the object of my invention to provide a latching-releasing mechanism that will be free from such defects.

To that end I have provided the mechanism shown in the accompanying drawings in which:

Fig. 1 is a horizontal section on the line 1—1 of Fig. 2.

Fig. 2 is a vertical section on the line 2—2 of Fig. 1.

Fig. 3 is a detail vertical section on the line 3—3 of Fig. 2.

Fig. 4 is a perspective view of the spring re-
tainer plate.

In the drawings in which like numerals and letters of reference indicate like parts in all the figures, 1 represents a portion of a refrigerator case having a doorway 10. The case includes a suitable frame 2, 2, 2^a, 2^b, 2^c sheathed on the outside by a metal sheath 26 (see Figs. 1 and 3).

The frame of the case is recessed as at 3 to receive a push rod body or bracket 6 which is screwed (at 7) to a face plate 4 which covers the recess 3 and is rigidly held in place by screws 5.

8 is a rubber strip into which one edge of the doorway trim frame 9 is set. The trim 9 (metal) has a slot 9^a for the strike portions 11^b, 11^d to pass. The strike 11 is secured to plate 4 by screws 11^c and to the frame 2 by a screw 11^f which passes through the strip 8.

Pivoted in the body 6 at 13 is a bell crank lever 12 having bifurcated ends 12^a, 12^b.

A push rod 16 is pivoted at 15 in the end 12^a while a linkage rod 19 is pivoted at 14 in the end 12^b. A spring 17 on the rod 16 between the lever 12 and the plate 4 continuously tends to retract the rod while a stop pin 18 limits the forward movement of the rod 16. The end of the rod which projects into the bifurcated end 12^a is flattened as at 16^a while the free end of the rod is bevelled as at 16^b so that the bevelled surface will register with the working face of the strike when the push rod is in its projected position and give an initial outward push when the pedal 24 is depressed by the foot of the operator.

2

The linkage rod passes down through an opening 2^x to beneath the bottom portion 2^c of the box or case 1 and passes through a passage 24^a in a treadle 24. The treadle 24 is pivoted at 23 to the ears 21^a of a treadle bracket 21 that is secured against the base trim plate 20 by screws 22. The linkage rod 19 has a rod catch 25 held by a set screw 25^a and located against the underside of the treadle. The treadle projects slightly beyond the front face of the case as shown in Figs. 1 and 3. The front rim 26 of the case terminates short of the treadle 24 (see Fig. 3).

The strike 11 includes a hump 11^a, a depression 11^b, a flat portion 11^c, and outwardly extended portion 11^d terminating in a foot 11^e that lies against the trim 9 (Fig. 1). That portion of the strike 11 which extends from the strip 8 to the hump 11^a is inclined at an angle of approximately 15° to the front face of the case while the end 16^b is inclined at about a 20° angle, the purpose of which will later more fully appear.

27 indicates the door which is hinged at the side remote from the latch in the usual manner (not shown since the hinging of the door is conventional and not part of the present invention, see for example the hinging of the door 10 in Patent No. 1,979,165 to McLean, October 30, 1934).

The door has a frame 27^a, 27^b, 27^d sheathed on the outside as at 44 and metal lined on the inside as at 42. The door is recessed at 27^c to receive the latching device which includes a catch body 28 having parallel sides 28^a with flanges 28^b (Fig. 2) for screws 29 which secure the body to the liner 42.

The catch is a peculiar form and is constructed of two outer plates 31 and a set of intermediate or filler plates 32 held together by a rivet 34 and a pin 30. The catch is pivoted on the pin 30 that is mounted in the walls 28^a. The catch at its latching end is of a hook shape, the hook passing through a slot 42^a and at its free end it carries a roller 33 on a pin 35. When in its latching position the roller 33 lies in the depression 11^b of the strike after passing over the hump 11^a (Fig. 1).

The other end of the catch is pivoted at 41 to a guide pin 40 that lies within a spring 38. A spring abutment ring 39 lies on the pin 40 against the catch and one end of the spring while the other end of the spring lies against a fiber face plate 36.

37 is a spring retaining plate having a tongue 37^a which cooperates with the catch body 28 in holding the spring against sidewise displacement. The body 28 has a stop tongue 28^c for the catch.

The provision of the 20° bevel 16^b on the outer end of the push rod 16 gives the door, when unlatched, an initial outward impulse when the pedal 24 is depressed by the foot of the operator, which, assisted by the spring 38, throws the door open to an angle of approximately 45°.

The gasket 43 is of a sufficiently resilient construction to make an air tight seal under the action of the catch spring 38 via the catch and strike and yet allow sufficient give for the roller 10 to be forced over the hump with ease.

From the foregoing it will be seen that I have provided a very rugged, compact assembly which will readily serve its intended purposes free of structural and mechanical deficiencies.

What I claim is:

In a refrigerator, comprising a door frame, and a door for said frame having an outer wall, a strike mounted on said door frame, a push rod mounted in said door frame and adapted to be 20 projected through said strike, a catch pivoted at one end to said door and having at the other end thereof a hooked end, a guide pin pivotally connected to the pivotal end of said catch and extending toward said door outer wall, a spring 25 encircling said pin and interposed between said door outer wall and said catch pivoted end, said

spring normally urging said hooked end into engagement with said strike when said door is in closed position, and means for operating said push rod for projecting it against said hooked end of said catch to pivot said catch and disengage said hooked end from said strike and simultaneously compressing said spring against said door outer wall for urging said door to open position.

PAUL H. BRINKOETER.
